Attorney.

UNITED STATES PATENT OFFICE.

PETER BROADBOOKS, OF BATAVIA, NEW YORK.

VISE.

1,317,347.

Specification of Letters Patent. Patented Sept. 30, 1919.

Application filed January 11, 1919. Serial No. 270,675.

To all whom it may concern:

Be it known that I, PETER BROADBOOKS, a citizen of the United States, residing at Batavia, in the county of Genesee and State 5 of New York, have invented certain new and useful Improvements in Vises; and I hereby declare that the following is a full, clear, and exact description thereof, reference being had to the accompanying drawings, which form part of this specification.

This invention relates to so-called quick-action bench vises, in which the movable jaw may be quickly adjusted relatively to the fixed jaw until they are separated to an 15 extent approximately equal to the thickness or width of the object to be gripped thereby, and then the movable jaw may be screw-adjusted to positively engage and clamp such object.

20 The invention relates particularly to the novel combined bar clutch and support of said vises, which greatly lessens the cost of manufacture of the vises without impairing their efficiency.

25 In the accompanying drawings I have illustrated one practical form of vise embodying the invention and will explain same with reference thereto to enable others to understand and use the same, but I do 30 not consider the invention limited to the particular construction shown and therefore refer to the claims to summarize the essential features of the invention and the novel details of construction and novel combinations of parts therein for all of which protection is desired.

In said drawings:

Figure 1 is a side elevation of a vise embodying my improvements, showing the vise 40 closed in full lines and opened in dotted lines.

Fig. 2 is a longitudinal vertical section through Fig. 1.

Fig. 3 is an enlarged vertical section on line 3—3, Fig. 1.

Fig. 4 is an enlarged sectional view of the sliding bar and combined clutch and support engagetherewith.

Fig. 5 is an enlarged side view of the combined clutch and support shown in Fig. 1.

This vice as shown comprises in general a main or fixed jaw 1; a slidable bar 3 ad-

justably supported in an opening in the standard supporting jaw 1; and a front or movable jaw 5 supported upon and movable 55 with bar 3, and also slidable upon this bar.

The rear or fixed jaw 1 is formed with or attached to a standard 1^a preferably formed with or rigidly attached to a base plate 1^b, which can be fastened in any suitable manner to the support, or bench, upon which the vise is to be mounted.

The standard 1^a has a longitudinal slot 1^b through which the slidable bar 3 extends, as shown in the drawings.

65 The sliding bar 3 may be of any desired length, according to the maximum width of objects which the vise is intended to grip. Said bar 3 preferably has a slot 3^a in its lower side connecting with a superposed enlarged longitudinal bore 3^b in the bar, said bore forming a slideway extending from the rear end of the bar toward the front thereof. As the slideway 3^b is wider than the slot 3^a the slideway is adapted to 70 engage and retain the head of the combined clutch member and support, hereinafter explained.

75 Secured within the slot 1^b in any suitable way is a combined clutch member and support, which in the form shown comprises a foot 2^a, a stud or standard 2^c rising therefrom, and a head or combined bearing and clutch member 2^d—2^e; the standard 2^c and head 2^d—2^e are preferably formed integral, 80 and they may also be formed integral with the base 2^a, or separate, and attached thereto. The combined clutch member and support can be made separate of steel and tempered and then attached to the jaw. Preferably I make the clutch member and support integral and directly connect them with the base plate or form them therewith, so that the clutch member and support may be assembled separately from the fixed jaw, and 85 inserted or removed therefrom as a unit, being readily attachable thereto and detachable therefrom.

90 As shown in Fig. 1 the foot 2^a is preferably secured by a screw 2^b to the base plate 1^b, and the upstanding standard 2^c rises from the base and extends through the narrow slot 3^a in the bottom of bar 3, and the head 2^d—2^e on the top of this supporting

portion 2^c operates within the slideway 3^b in bar 3 and serves both to support and clutch bar 3 as hereinafter explained.

In the construction shown in Figs. 1-4 5 the bar 3 rests upon the top of the inner end 2^d of the head, as indicated at the point 2^x, Figs. 2 and 3, while the rear end and underside of the part 2^d of the head engages the underlying portions or lips 3^c of the 10 slideway at the opposite sides of the slot 3^a, as indicated at the point 2^z (Figs. 2 and 4); when the jaw 5 is lowered, or adjusted to clamp an object against jaw 1.

The top surface of the end 2^d of the head 15 is inclined or beveled slightly downwardly and outwardly as shown so that by lifting jaw 5, to relieve the pressure at points 2^x and 2^z, the bar 3 can be freely slid back and forth on the part 2^d of the head by reason 20 of the slight taper thereof; but when jaw 5 is released its weight will cause bar 3 to bear upon the end 2^d of the head at point 2^x and the rear end and underside of the part 2^d of the head will engage the ribs or 25 lips 3^c of the slideway 3^b at points 2^z, and the parts will thus be engaged and the bar 3 clutched and locked in place when an object is gripped between the jaws. The shape 30 of the head may be varied, provided its essential features are retained.

The front jaw 5 is complementary to the 35 jaw 1 and has its shank formed with a mortise 5^b for engagement with the front end of the sliding bar 3, on which jaw 5 is slidably mounted. The outward movement of the 40 jaw 5 on and relative to the bar 3 may be limited by a stop screw 3^d tapped into the underside of the sliding bar 3.

The jaw 5 may be adjusted on bar 3 by 45 any suitable means. As shown a screw 6 is tapped into the outer end of bar 3; the outer wall 5^a of this mortise forms a wear plate against the inner face of which a collar 6^a on the screw 6 bears, while the head 6^b of the screw bears against the outerface of 50 wall 5^a. The collar and head compel the jaw 5 to slide in or out on bar 3 when the screw is turned by the usual hand-bar 6^c. The head of the hand-screw 6 being placed near the 55 upper edge of said jaw 5, said screw-head will take the greatest part of the strain off from the lower bearing 5^b of said jaw.

The outer upper end of the front jaw 5 is formed with a shield 5^e above the screw 60 head to prevent filings from dropping between the head of the screw and the jaw.

The combined clutch and support being 65 integral can be rigidly attached to the base plate 1^a within the opening in the jaw as shown; and can be readily adjusted or replaced with one screw or bolt 2^b; it may also be permanently attached to the vise, and by having the clutch integrally formed with the support it can be made with larger bearings and stronger.

Actual practical advantages of the construction shown in Figs. 1 to 4 are the combined clutch and support for bar 3; such member can be more readily attached to a vise; it is more solid and firm; it can be 70 made integral; it can be quickly removed; and vises with such combined clutch and support members will cost less to manufacture.

The front jaw, as shown, can be made 75 smaller and lighter in weight than heretofore, and therefore will be more easy to lift in unclutching the bar to quickly adjust the jaws to the object to be clamped.

The sides of the body of the stationary 80 jaw, and the sides of the sliding bar are preferably plain and smooth, so that there is nothing to interfere with work placed in the vise, or in which filings lodge.

I claim:

1. In a vise, a fixed jaw having an opening through its standard; a sliding bar extending through said opening and having a slideway therein, and a slot in the bottom of said sliding bar communicating with said slideway; a movable jaw slidably attached to said bar; a combined clutch and support within said opening and passing through said slot and having a head adapted to engage said slideway whereby the sliding bar 90 will be rigidly held locked when the end of the bar carrying the movable jaw is lowered and the jaws clamped upon an object; said combined clutch and support serving as a support upon which said sliding bar 95 may be slid to and fro in adjusting it.

2. In a vise of the character shown and described, a jaw having an opening through its shank for a sliding bar; a plain smooth surfaced rectangular sliding bar having a 105 longitudinal slideway therein and a slot connecting with said slideway, a movable jaw slidably attached to said bar to clamp the work between the jaws; a combined clutch and support secured in the bottom of said opening and below the bar having a standard passing through the slot and a head on the standard engaging said slideway, the lower side of the head being adapted to contact with the lower walls of said slideway 110 whereby the sliding bar will become automatically locked to said clutch when the end of the bar carrying the movable jaw is lowered and the jaws clamped upon an object, said head being tapered on its upper 115 side and serving as a support upon which said sliding bar may be slid to and fro in adjusting the bar.

3. In a vise of the character shown and described, a jaw having an opening through its standard for a sliding bar; a plain smooth surfaced rectangular sliding bar having a 125 slideway internally milled therein and a slot connecting with said slideway; a movable jaw slidably attached to said bar to clamp 130

the work between the jaws; a combined clutch and support in said opening and below the bar and having a head within said slideway, the inner upper end of the head 5 supporting the bar when the end of the bar carrying the movable jaw is lowered or the jaws clamp an object, and the lower side of the outer end of the head being adapted to contact with the lower walls of said 10 slideway to automatically lock the sliding bar when the bar is lowered or the jaws clamped upon an object; said head also serving as a support upon which said sliding bar may be slid to and fro in adjustment, as and for the purpose specified. 15

4. In a vise of the character described, a fixed jaw having an opening through its standard, a sliding bar passing through said opening and having a slideway therein, a 20 movable jaw on the outer end of said bar, an integral combined clutch and support attached to the bottom of and within said opening and having a part extending to the slideway and a head thereon within said 25 slideway; said head having one end adapted to engage the lower side of the guideway when pressure is brought to bear upon the work by the movable jaw.

5. In a vise, a fixed jaw having an opening 30 through its standard; a sliding bar extending through said opening and having a slideway therein, and a slot in the bottom of said sliding bar communicating with said slideway; a movable jaw slidably attached to said 35 bar to clamp the work between the jaws; a combined clutch and support detachably attached to the base of the standard within said opening and passing through said slot and having a head adapted to engage the 40 lower and the upper surface of said slideway whereby the sliding bar will be rigidly held locked when the end of the bar carrying the movable jaw is lowered and the jaws clamped upon an object; said combined 45 clutch and support serving as a support upon which said sliding bar may be slid to and fro.

6. In a vise of the character described, a rear jaw and standard having an opening 50 therethrough, a sliding bar extending through said opening and having a slideway therein and a slot in the bottom of said slideway, a movable jaw slidably attached to said bar; a combined clutch and support 55 secured in said opening and having a part extending through the slot into the slideway, and having a flanged head in the slideway adapted to engage with the lower and the upper surfaces of said slideway whereby 60 the sliding bar will be both supported and rigidly locked when work is clamped between the jaws; said head also serving as a support upon which said bar may be slid to and fro in adjustment, substantially as 65 described.

7. In a quick adjusting bench vise, the combination of a jaw body having an opening therethrough for the slide bar; a plain surfaced rectangular slide bar having a 70 slideway internally formed therein, a combined clutch and support member attached to said body within said opening and below the slide bar; said member having a flanged head engaging said slideway; the flanges of the head being adapted to contact with the 75 lower wall of said slideway whereby the sliding bar will be supported on and automatically locked by said head when the jaws of the vise are in their normal upright position; and a movable jaw slidably attached to 80 said bar, substantially as described.

8. In a vise of the character described, a fixed jaw having an opening through its standard, a sliding bar passing through said opening and having a slideway therein, a 85 movable jaw on the outer end of said bar, an integral combined clutch and support attached to the bottom of and within said opening and having a part extending to the slideway and a head thereon within said 90 slideway, said head having one end adapted to engage the upper side of the guideway when pressure is brought to bear upon the work by the movable jaw, the inner end of said head being tapered on its underside and the outer end of said head being tapered at its upper side so that the bar may be tilted on the head and supported thereby while being adjusted longitudinally. 95

9. In a vise, a jaw standard having an opening, a sliding bar adapted to slide through said opening, a combined clutch and support within said opening having a head adapted to grip said sliding bar and hold same in operative position; a movable jaw having a mortise to engage the front end of said bar, a screw engaging said bar and passing through the outer wall of the mortise; a collar and a head on the screw adapted to engage opposite sides of the outer wall of the mortise to cause the screw to move said jaw; and a stop to limit the movement of said jaw on the bar. 100

10. In a vise of the character described, a rear jaw and standard having an opening 115 therethrough, a sliding bar extending through said opening and having a slideway, a movable jaw slidably attached to said bar; a combined clutch and support in the opening of the standard having a part extending into the slideway and adapted to engage with both the lower and the upper surfaces of said slideway to support and rigidly lock the sliding bar when work is clamped between the jaws; said part also serving as 120 a support upon which said bar may be slid to and fro in adjustment.

11. In a quick adjusting bench vise, the combination of a jaw body having an opening for the slide bar; a slide bar passing 130

through said opening and having a slideway, a combined clutch and support member attached to said body within said opening and below the slide bar; said member having a head engaging said slideway and adapted to support and automatically lock said bar when the jaws of the vise are in their normal

upright position; and a movable jaw slidably attached to said slide bar, substantially as described.

10

In testimony that I claim the foregoing as my own, I affix my signature.

PETER BROADBOOKS.
